UNITED STATES PATENT OFFICE

ORSON J. BLAKESLEY, OF DENVER, COLORADO, ASSIGNOR TO THE BLAKESLEY KEYLESS LOCK COMPANY, OF DENVER, COLORADO.

KEYLESS LOCK.

992,400.

Specification of Letters Patent. Patented May 16, 1911.

Application filed April 26, 1909, Serial No. 492,426. Renewed October 5, 1910. Serial No. 585,518.

To all whom it may concern:

Be it known that I, ORSON J. BLAKESLEY, a citizen of the United States, residing in the city and county of Denver and State of Colorado, have invented certain new and useful improvements in Keyless Locks; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in keyless locks of the class set forth in my previous Patent No. 866,567, dated September 17th, 1907, and an application Serial No. 373,545, filed May 14th, 1907, allowed Sept. 26th, 1908.

My present invention relates to certain novel features of construction, whereby the mechanism disclosed in my previous patent and application, is greatly simplified, all of which will be fully understood by reference to the accompanying drawing in which is illustrated an embodiment thereof.

In this drawing, Figure 1 is a top plan view of my improved lock. Fig. 2 is a similar view with the cover of the case removed. Fig. 3 is a section taken on the line 3—3, Fig. 2. Fig. 4 is a view similar to Fig. 2, but with the revolving disk removed, disclosing the catch or latch, the catch spring, the spider-spring and the button holder. Fig. 5 is a sectional view taken on the line 5—5, Fig. 3. Fig. 6 is a fragmentary sectional detail view of the lock showing one of the buttons in one of its relations with the other parts and on a larger scale. This is a section taken on the line 3—3, Fig. 2 looking in the direction of the arrow. Figs. 7, 8, 9, and 10 are sections taken on the lines 7—7, 8—8, 9—9, and 10—10, respectively, of Fig. 6, the button only being sectionized. Fig. 11 is a detail view of the catch with its spring in position. Fig. 12 is a detail view of the spring. Fig. 13 is a section taken through the case, illustrating one of the buttons when in its inactive position or when in the position allowing the revolving disk to enter one of the segmental slots or recess thereof. Fig. 14 is a similar view showing the button when in a position after giving it approximately one-third of a rotation from the position shown

in Fig. 13. In this view the button must be pressed downwardly in order to permit the revolving disk to move to the unlocked position. Fig. 15 is a similar view after the button has been turned two-thirds of a revolution from the position shown in Fig. 13. When in the position shown in Fig. 15, the button must be moved upwardly in order to allow the revolving disk to move to the unlocked position. Fig. 16 is a view of the spring shown in Fig. 12, viewed in the direction of arrow 16, Fig. 12. Fig. 17 is a fragmentary section taken through the bottom of the casing on the line 17—17 of Fig. 5 cutting the button-holder, the parts being shown on a larger scale.

The same reference characters indicate the same parts in all the views.

Let the numeral 5 designate the case which as shown in the drawing is circular in shape and composed of a bottom plate 6 and a surrounding flange 7 extending at right angles to the bottom. The upper edge of the case is recessed to form an interior shoulder 8 upon which the cover 9 rests. The parts of the lock are held in operative relation by a center rivet 10.

Surrounding the rivet 10 in the bottom of the case is a washer 12 and also surrounding the rivet above the washer 12 is a second washer 13 which is surrounded by the button holder 14, consisting of a plate having a central perforation in which the washer 13 fits and having openings 15 through which pass the extremities of a number of buttons 16 which extend transversely through the case of the lock. The portions 17 of these buttons which pass through the openings 15 are triangular in shape. The openings 15 have circular portions 18 which when engaged by the parts 17 of the buttons, allow the latter to turn freely. Communicating with the parts 18 of the openings 15 are parts 19 in which the portions 17 of the buttons are adapted to fit closely, whereby the buttons when engaging the parts 19 of the said openings are locked against rotation. When the parts of the lock mechanism are assembled and in their normal position, the parts 19 of the openings 15 are engaged by the triangles 17 of the buttons, whereby the latter are locked against rotation. The button holder is held in such normal position by a lip 20 projecting slightly downwardly from the bottom of the said holder and

engaging a shallow recess 21 formed in the adjacent surface of the bottom of the case.

When it is desired to change the combination, which is accomplished by giving one or more of the buttons 16 a partial rotation, the lip 20 of the button holder, is disengaged from the recess 21 by lifting the lip out of the recess, after which the holder may be turned to bring the circular portions 18 of the openings 15, into the position to allow any button to be turned freely. After this is accomplished or after the pins have been properly adjusted, the button holder is returned to its normal position or that in which the parts 19 of the openings 15 engage the triangular portions of the buttons and lock them against rotary movement.

The washer 13 is somewhat thicker than the button holder, to prevent the latter from being clamped or secured against movement when the parts are assembled.

The button holder 14 is provided at its outer edge with an upwardly projecting lip 4 which when the button holder is in the unlocked position, occupies a position in front of the opening 46 in the edge of the case to permit the entrance of the hooked extremity 30 of the hasp. This lip is so located that if the user of the lock, should forget to return the button holder to its proper position after changing the combination, the hooked extremity 30 of the hasp would perform this function automatically as soon as the hasp is caused to assume the locked position, since as the said extremity of the hasp moves inwardly, it will engage the lip 4, and move the button holder toward the right (see Figs. 4 and 5), sufficiently to cause the lip 20 to engage the recess 21 in the bottom of the case.

Above the washer 13 and resting thereon is a third washer 22 having a central opening through which the rivet 10 passes. Above the washer 22 and resting thereon is a spider spring 23 whose central portion is perforated to receive the rivet 10. From its central portion spring arms 24 extend radially, the outer extremities of the said arms engaging circumferential grooves 25 in the buttons 16, whereby the latter are normally held in a predetermined position with reference to the other parts of the mechanism.

The central portion of the rivet 10 is enlarged as shown at 26 and passes through a perforation 27 formed in a catch 28 which is pivotally mounted upon the rivet. The outer extremity of the catch 28 is provided with a laterally disposed catch member 29 adapted to engage the hook extremity 30 of a hasp 31, when the parts are in the locking position.

The inner or pivotal extremity 32 of the catch is embraced exteriorly by a spring 33 having arms 34 and 35. This spring is pro-

vided with a lip 36 projecting into a recess 37 formed in the pivotal extremity of the catch. The member 34 of the spring has its outer extremity, located in such proximity to the catch member 29, that when the hasp is in the locked position, its inner extremity bears against the spring member 34 and places the same under tension. At the same time the spring member 35 engages a lip 38 formed on a revolving plate 39, the lip 75 engaging the spring member 35 upon the left or opposite the location of the hasp extremity 30 with reference to the spring member 34. When the hasp is in the locked position, the revolving disk 39, is prevented from moving toward the left, by virtue of the position of one or more of the buttons 16, which are so arranged that the arms 40 of the revolving disk are prevented from entering any one of the slots A, B and C 85 formed in each button. These slots are simply segment-shaped recesses formed in the pin and occupying three different horizontal planes when the lock case is in the horizontal position.

Attention is called to the fact that in describing the lock mechanism and the relations of the various parts to one another when assembled, it is assumed that the lock case occupies a horizontal position, with the bottom of the case lowermost and its cover uppermost.

The segmental slot A is uppermost in each button; the segmental slot C is lowermost; while the slot B is centrally located.

As shown in the drawing, there are eight buttons, each button being identical in construction with every other button. If all of the buttons were in the same relative position or that shown in Fig. 13, each button being adjusted to bring its slot B into the same plane with one of the arms 40 of the revolving disk 39, the disk together with the catch 28 would normally assume the unlocked position and the inner extremity of the hasp 31 would not be engaged by the catch member 29. However, by turning one or more of the buttons to the position shown in Fig. 14 or Fig. 15 as the case may be, whereby one of the arms 40 of the revolving disk is prevented from entering the slot B, it will be necessary to move the button either up or down within the case in order to allow the revolving disk, together with the catch 28 to move to the unlocked position.

The three different positions in which any button may be placed are respectively illustrated in Figs. 13, 14 and 15. In Fig. 13 the central slot B is in the plane of an arm 40 of the revolving disk, while in Fig. 14 the position of the slot B is such that the arm 40 cannot enter it; this is also true when the button is in the position shown in Fig. 15. In Fig. 14, the slot A is so ar- 130

ranged that if the button is pressed downwardly, the last named slot will be brought into the plane of an arm 40 of the revolving disk allowing the said arm to move into the 5 slot and permitting the disk and catch to move to the unlocked position. In Fig. 15 the slot C is so arranged that if the button is pushed upwardly a sufficient distance to bring an arm 40 of the revolving disk into 10 the plane of the slot C, the arm 40 will enter the last named slot allowing the revolving disk and catch to move to the unlocked position.

If two buttons of the set are in the relative 15 positions shown in Figs. 14 and 15, in order to open the lock or release the hasp, it will be necessary for the operator to press down upon one of these buttons, namely, the one shown in Fig. 14, and up on the other 20 button, namely, the one shown in Fig. 15.

Attention is called to the fact that the cover of the lock case is provided with openings 41 through which the upper extremities 42 of the various buttons protrude; while 25 the bottom of the case is provided with openings 43 through which the lower extremities 44 of the buttons protrude. Both extremities 43 and 44 of the various buttons, protrude a sufficient distance beyond the 30 case, to allow for the convenient manipulation of the buttons by upward or downward pressure upon their exposed extremities, and only the person who knows the combination of the lock or just which buttons to press 35 and in which direction to press them, can open the lock. In setting the combination, it is evident that any desired number of the buttons may be so placed that they must be manipulated in order to open the lock.

40 If three buttons are so adjusted that the revolving plate cannot normally enter their recesses B, they may be so arranged that all of them may be properly manipulated by pressing downwardly or upwardly; or one 45 of them may be set to move downwardly while the other two must be moved upwardly or vice versa. From this it will be understood that there are a great many different possible combinations obtainable by 50 adjusting the eight buttons in question.

Attention is called to the fact that the buttons are held in their normal position by virtue of the engagement of the spring arms 24 of the spider spring 23. These spring 55 arms also serve to return the buttons to their normal position, after they have been pressed in either direction for unlocking purposes, that is to say after the slots which are engaged by the revolving disk in order 60 to allow it to move to the unlocked position, have been disengaged, by the opposite movement of the revolving disk. The revolving disk is also provided with an interiorly projecting lip 45, which enters a recess 3 formed 65 in the outer end of the catch 28.

One extremity of the hasp enters an opening 47 formed in the lock case, and is pivotally connected with the case by means of a pivot 48 whose opposite extremities enter perforations formed in the bottom and cover 70 of the case respectively. The inner extremity 49 of the pivoted end of the hasp projects inwardly and is provided with a recess 50 which is engaged by one extremity 75 of a leaf-spring 51, whose opposite extremity 52 is anchored in an opening formed in the bottom of the case, the said spring extremity being riveted or otherwise suitably secured to the case. The spring extremity 52 passes through a slot 53 formed in the 80 button holder, the said slot being of sufficient length to permit the button holder to be moved back and forth within reasonable limits for the proper performance of its function.

85 The spring 51 is under such tension when the hasp is in the locked position, that as soon as the extremity 50 of the hasp is released, the action of the spring upon the opposite end of the hasp, will instantly 90 throw the hooked end of the latter outwardly, whereby the interiorly projecting extremity 49 of the hasp is caused to engage the catch 28, and move the latter to the position bringing the catch member, in front of the opening 46 within the edge of the case, whereby, as the hooked extremity of the hasp enters said opening, it is caused to engage the catch and interlock therewith by virtue of the tension of the catch.

95 Located above the revolving disk 39 but separated therefrom, is a washer 54 which rests upon a shoulder 55 formed upon the center rivet 10, whereby the washer is spaced from actual contact with the revolving disk, thus preventing the clamping of the moving parts of the mechanism to interfere with their proper movements, when the parts are assembled. It must be understood that the center rivet is upset or riveted at both ends 100 in order to make it impossible to gain access to the lock when the latter is in use.

105 The mechanism is so constructed that after the lock is completed and the center rivet secured by upsetting its opposite extremities as shown at 56 and 57, there is no necessity for gaining access to the interior of the case so far as the use of the lock is concerned, except for changing the combination, and this is accomplished by inserting a small instrument as a knife blade or small screw driver, into the hasp opening 46 in the edge of the case; in order to disengage the lip 20 from the recess 21 formed in the bottom of the case, in order to move 110 the button holder sufficiently in the direction of the arrow in Fig. 5, to bring the triangular portions 17 of the buttons into the circular parts 18 of the openings 15 in the button holder. After this is done, the 115 120 125 130

combination may be changed by giving one or more of the buttons a partial rotation, whereby the position of the button with reference to that of the revolving disk 39, may be changed from any one of the positions shown in Figs. 13, 14 and 15 to any other one of said positions. It is evident that if all of the buttons except two are in the positions shown in Fig. 13, and those two are 10 in the positions shown in Figs. 14 and 15, the lock may be opened, by pressing downwardly upon the button in the position shown in Fig. 14 and pressing upwardly upon the button in the position shown in Fig. 15, since in that event the segmental slot A of the button shown in Fig. 14 and the segmental slot C of the button in the position shown in Fig. 15, will both be brought into the same plane as the slots B 20 of all the other buttons or those in the position shown in Fig. 13. In this event, the arms 40 of the revolving disk 39 which is under tension to move in the direction indicated by the arrows in Figs. 13, 14 and 25 15, will move into engagement with the slots A and C, respectively of the buttons 14 and 15 and the slots B of all the other buttons, this movement being sufficient to allow the catch 28 to move in the same direction or 30 that indicated by the arrow in Figs. 2 and 4, to disengage the catch member 29 of the catch from the hooked extremity 30 of the hasp, whereby the latter which is under tension by virtue of its connection with the 35 spring 51, is thrown to the unlocked position or that indicated in Fig. 5.

It will be understood from the explanation heretofore given that when the hasp is in the locked position (see Figs. 1, 2 40 and 3), the pressure of the inner extremity 30 of the hasp upon the spring member 34, places the said spring member under tension and gives the catch a tendency to move in the direction of the arrow in Figs. 2 and 45 4, but this it cannot do because the lip 38 of the revolving disk is in direct engagement with the spring member 35, whereby the tension of the catch or its tendency to move in the direction stated is prevented, 50 since the movement of the revolving disk in the same direction is prevented by reason of the fact that the buttons which must be actuated to unlock the disk as those in the positions shown in Figs. 14 and 15, prevent the movement of the revolving disk. 55 In this connection, it should be stated that the spring member 35 is stronger or stiffer than the spring member 34 and is virtually a rigid part of the catch so far as the function of the spring member 35 is concerned. In other words, the spring member 35 will not yield under the influence of the pressure applied by the inner extremity of the hasp to the spring member 34, since otherwise the catch would move in the direction

of the arrows in Figs. 2 and 4 notwithstanding the revolving disk remained stationary. The spring member 35, however, does yield sufficiently to allow the hasp extremity 30 to enter the lock casing, this being necessary when the hasp extremity first engages the catch member 29 of the catch. In this case, the revolving disk cannot move in the direction necessary and consequently the catch must move and the spring member 35 must yield sufficiently to permit this movement, but as soon as the hasp end 30 is forced past the catch member 29, the latter immediately returns under the influence of the spring member 35 to interlock with the inner extremity of the hasp.

In further explanation of the operation of the lock, it may be stated that when the buttons necessary to be operated for unlocking purposes, are actuated, the parts 40 of the revolving disk immediately enter the slots of the buttons as heretofore explained. During this engagement, the buttons are retained in the actuated positions since the revolving disk prevents the return of the buttons to their normal positions under the tension of the arms 24 of the spider spring. However, as soon as the revolving disk assumes the said position, the hasp is thrown outwardly to the position indicated in Fig. 95 5 and during such movement, the end 49 of its pivoted extremity, acts upon the catch to throw the latter in the direction opposite that indicated by the arrow in Figs. 2 and 4 and this movement of the catch imparts 100 a corresponding movement to the revolving disk returning it to its normal position, releasing the buttons and allowing them to return to their normal position under the influence of the spider spring, since the outer 105 shoulder 58 at one end of the recess 3 formed in the catch, acts upon the lip 45 of the revolving disk, the said lip being in engagement with the said shoulder at all times, except during the short interval when the inner end 30 of the hasp is pressing on the catch member 29 of the catch to move the latter in the direction of the arrow in Fig. 4, to allow the hasp to enter the case, after 110 which the catch returns to the locking position in engagement with the lip 45. It will be seen by reference to Fig. 4 that normally there is a space between the shoulder 59 of the recess 3 and the lip 45 of the revolving disk, to allow the catch to move toward 120 the left (see Fig. 4), a sufficient distance while the lip 45 remains stationary, to allow the hasp end 30 to enter the case and assume the locking position.

From what has been said heretofore, it 125 will be understood that the combination of the lock may be changed by giving one or more buttons a partial rotation. Each partial rotary movement of each button must be equal to one-third of a complete revolu- 130

tion, by virtue of the fact that the buttons where they pass through the buttonholder are triangular in cross section. In order that the operator may understand when the necessary movement is given any button, for changing the combination, the protruding extremity of the button on one side of the case herein designated the top, is provided with three radial marks 1 equidistantly located. Also arranged on top of the disk, is a number of dots or marks 2, toward one of which, one of the radial marks of each button always points. These marks designated 1 and 2 are to enable the operator to know when he has moved a button far enough to change the combination. Hence, in turning any button for the aforesaid purpose, the operator will move the same until the mark 1 next in the rear is brought into line with the mark 2 on the case or until the second mark next in the rear is caused to point toward the mark 2. In either case, the button will be adjusted sufficiently to change the combination. This is true of all of the buttons.

As there is the same number of marks 1 and 2 upon each button, one not knowing the combination cannot tell which buttons to push, or in which direction to push them for unlocking purposes.

Having thus described my invention, what I claim is:

1. In a lock the combination with a case, of buttons passing transversely therethrough and movable therein, each button having a number of slots arranged in different planes, a revolving disk occupying the same plane as one slot of all the buttons, the latter being capable of adjustment to bring the other slots into the plane of the disk.

2. In a lock the combination with a case, of buttons passing transversely therethrough and movable endwise therein, the button extremities being exposed for manipulating purposes, each button having a number of slots arranged in different planes, a revolving disk occupying the same plane as one slot of all the buttons when the latter are in their normal position, the buttons being capable of endwise adjustment to bring the other slots into the plane of the disk.

3. In a lock the combination with a case, of buttons passing therethrough and movable endwise therein, each button having a number of slots arranged in different planes and in different relative positions around the button, the button extremities being exposed on opposite sides of the case for manipulating purposes, a revolving disk occupying the same plane as one slot of all the buttons when the latter are in their normal position, the buttons being capable of adjustment to bring the other slots into the plane of the disk.

4. In a lock the combination with a case,

of buttons passing transversely therethrough and movable endwise therein, each button having a number of slots arranged in different planes and in different relative positions around the button, a revolving disk occupying the same plane as one slot of all the buttons when the latter are in their normal position, the buttons being independently rotatable in the case to bring the slot of any button normally occupying the plane of the disk out of register with the latter, to prevent the entrance of the disk, while another slot of the same button is brought into position above or below the disk, to allow the disk to enter when the button is moved endwise in the proper direction.

5. A lock including a case and buttons

passing transversely therethrough and end-

wise movable therein, the buttons being ro-

tatable and having circumferential grooves,

and a spring engaging the said grooves of

all the buttons for normally retaining them

in a predetermined position.

6. A lock including a case and buttons

passing transversely therethrough and end-

wise movable therein, the buttons being ro-

tatable and having circumferential grooves,

and a spider spring having arms engaging

the said grooves of the respective buttons

and normally retaining all buttons in their

normal or predetermined position.

7. A lock including a case, buttons pass-

ing transversely therethrough and endwise

movable therein, and having slots arranged

in different planes and in different relative

positions around the button, a revolving

disk lying in the plane of one slot of a

number of buttons, the said slots being in

position to register with the disk, the other

buttons being capable of movement to bring

another slot of each button into the plane

of the disk.

8. A lock including a case, of buttons

passing transversely therethrough, endwise

movable therein and having slots arranged

in different planes and in different relative

positions around the buttons, a revolving

disk lying in the plane of one slot of a num-

ber of buttons with which the slots register,

the other buttons being capable of move-

ment to bring another slot of each into the

plane of the disk and a spring for normally

retaining all of the buttons in a prede-

termined endwise position.

9. A lock including a case, a series of

buttons passing transversely therethrough

and endwise movable therein, the buttons

having slots arranged in different planes

and in different relative positions around

the buttons, a revolving disk lying in the

same plane as one slot of all the buttons, the

latter being rotatable to bring this slot of

any button out of register with the disk, the

said button being endwise adjustable to

bring another slot into register with the disk.

10. A lock including a case, a series of

buttons passing transversely therethrough

and endwise movable therein, the buttons

having slots arranged in different planes

and in different relative positions around

the buttons, a revolving disk lying in the

same plane as one slot of all the buttons, the

latter being rotatable to bring this slot of

any button out of register with the disk, the

said button being endwise adjustable to

bring another slot into register with the disk.

10. A lock including a case, a series of buttons passing transversely therethrough and endwise movable therein, the buttons having slots arranged in different planes and in different relative positions around the buttons, a revolving disk lying in the same plane as one slot of all the buttons, the latter being rotatable to bring this slot of any button out of register with the disk and endwise adjustable to bring another slot into register with the disk, and a spring for normally holding all of the buttons in a predetermined position of endwise adjustment.
- 15 11. A lock including a case, a series of buttons passing transversely therethrough and endwise movable therein, the buttons having slots arranged in different planes and in different relative positions around the buttons, a revolving disk lying in the same plane as one slot of all the buttons, the latter being rotatable to bring this slot of any button out of register with the disk, the said button being endwise adjustable to bring another of its slots into register with the disk, and means for positively holding all of the buttons against rotary movement.
- 20 12. A lock including a case, a series of buttons passing transversely therethrough and endwise movable therein, the buttons having slots arranged in different planes and in different relative positions around the buttons, a revolving disk lying in the same plane as one slot of all the buttons, the latter being rotatable to bring this slot of any button out of register with the disk, the said buttons being endwise adjustable to bring another slot into register with the disk and means for positively holding all of the buttons against rotary movement, each button having a part polygonal in cross section, said holding means comprising an adjustable plate having openings of such shape that when the plate is in one position of adjustment, the polygonal portions of the buttons are permitted to turn therein, while when the plate is in another position of adjustment, the polygonal portions of the buttons engage correspondingly shaped portions of the plate openings.
- 25 13. A lock including a case, a series of buttons passing transversely therethrough and movable therein, the buttons having slots arranged in different planes and in different relative positions around the buttons, a revolving disk lying in the same plane as one slot of all the buttons, the latter being rotatable to bring this slot of any button out of register with the disk, a button holding plate for positively locking all of the buttons against rotary movement, each button having a part polygonal in cross section, said button holding plate being adjustable and having openings of such shape that when the plate is in one position of adjustment, the polygonal portions of the buttons are permitted to turn therein, while when the plate is in another position of adjustment, the polygonal portions of the buttons engage correspondingly shaped portions of the plate openings, a hasp pivotally connected with the case at one end, its opposite end being adapted to enter an opening formed in the case the said button holding plate having a depending lip adapted to enter a recess formed in the bottom of the case.
- 30 14. A lock including a case, a series of buttons passing transversely therethrough and endwise movable therein, the buttons having slots arranged in different planes and in different relative positions around the buttons, a revolving disk lying in the same plane as one slot of all the buttons, the latter being rotatable to bring this slot of any button out of register with the disk, a button holding plate for positively locking all of the buttons against rotary movement, each button having a part polygonal in cross section, said button holding plate being adjustable and having openings of such shape that when the plate is in one position of adjustment, the polygonal portions of the buttons are permitted to turn therein, while when the plate is in another position of adjustment, the polygonal portions of the buttons engage correspondingly shaped portions of the plate openings, a hasp pivotally connected with the case at one end, its opposite end being adapted to enter an opening formed in the case, the said button holding plate having a depending lip adapted to enter a recess formed in the bottom of the case, the button holding plate having an upwardly projecting lip which when the depending lip is out of engagement with the said recess, is brought into the path of the hasp when entering its opening in the case, whereby the plate is automatically returned to its button holding position.
- 35 15. In testimony whereof I affix my signature in presence of two witnesses.
